Francis M. Jacobs Inventor
By Ernest E. Kelly, Jr. Attorney

UNITED STATES PATENT OFFICE

FRANCIS M. JACOB, OF COLUMBUS, MISSISSIPPI

COMBINED SEESAW AND MERRY-GO-ROUND

Application filed June 12, 1930. Serial No. 460,709.

My invention relates to an improvement in a combined see-saw and merry-go-round.

The object is to provide a see-saw and merry-go-round which is simple and sturdy in construction and which is capable of being used either as a permanent or as a portable fixture.

A further object of my invention is to provide a see-saw and merry-go-round which 10 may be adjusted for use by children of different sizes and weights. A see-saw of my construction may also be used by two or more persons, one teeter board being folded out of the way when not in use.

15 In the accompanying drawings:

Fig. 1 is a perspective view of the device, showing one teeter board in position for use, the other being broken away;

Fig. 2 is a plan view;

20 Fig. 3 is a vertical section through one set of teeter boards;

Fig. 3a is a fragmentary view of the teeter board support showing one means of fastening the same to the ground;

25 Fig. 4 is an enlarged sectional detail of the inner end of the teeter board, showing the board in position for use;

Fig. 5 is an enlarged sectional detail of the inner end of the teeter board, showing 30 the board folded up out of the way;

Fig. 6 is a section on the line 6—6 of Fig. 4; and

Fig. 7 is a detail of one of the teeter arms, partly in cross-section.

35 The column 2 of the see-saw is fastened to and supported by the base 4. The sleeve 6 is rotatably mounted on the column 2 and held between the lower bearing collar 8 and the upper bearing collar 10. Interposed between these bearing collars 8 and 10 and the sleeve 6 are the ball bearings 12.

On the revolving sleeve 6, the pivoted teeter arm supports 14 are mounted by means of the pins 16 projecting from the sleeve 6.

40 The teeter arms 18 are pivotally attached to the teeter arm supports 14 by means of the bolts 20 and are held in the desired position by the hand bolts 22.

45 As shown in Fig. 7, the teeter arms 18 are 50 made of solid material at the inner ends,

where they are affixed to the supporting arms 14, and are hollow at the opposite ends thereof for the purpose of holding the extensible arms 24, which arms are constructed with a slot 26 through which the bolt 28 in the teeter 55 arm 18 extends.

At the outer end of the extensible arms 24 are suitable seats 30 and a hand rail 32, which latter is held in suitable position by the metal strip 34. Beneath the hand rail and 60 at a distance further away from the seat is a metal strip bent to form a foot rest 36, the foot rest being secured to the arm 24 by means of a bolt 38. The seat 30 may be finished with a back 40, as shown in Fig. 1, or 65 it may be left with no back as illustrated in the other figures.

The curved resilient strip 42 is secured to the underside of the seat 30 by means of the screws 44, the strip 42 forming a skid or stop 70 to keep the end of the teeter board from digging into the ground.

The entire see-saw and merry-go-round may be adjusted vertically by either raising or lowering the sleeve 6 on the column 2 and 75 fastening same in the desired position by means of the collars 8 and 10 which are held in position by the set screws 46 and 48, respectively. The teeter arms 18 and the extension arms 24 are made telescopic so one 80 may slide within the other. Thus, when it is desired that the see-saw be used by children of different weights the extension arms 24 may be pulled out from the teeter arms 18 to the desired length to give one end of the 85 board a greater length than the other, thus increasing the weight on that end by placing the child thereon at a greater distance from the fulcrum.

When it is desired that only one teeter be 90 used at a given time, the other may be folded up and kept out of the way. To do this, it is only necessary to remove the bolts 22, fold the teeter boards into the position shown in dotted lines in Fig. 3 and replace the bolts 95 22 in the same holes in the supporting arms 14. When the boards are in this position the notch 50 in the projection 52 on the inward end of the teeter arm 18 will be in alignment with the holes in the supporting arms 14, so 100

that the bolt 22 may pass through the said notch, as illustrated in Fig. 5, and hold same in the upward position shown in Figs. 3 and 5.

In setting up the device for use, the screws 5 54 may be used to fasten the base 4 to the floor, if the device is to be used on a foundation such as a floor. If it is desirable to use the device on a lawn where the screws 54 could not be used, a stake 60 may be driven 10 into the ground, leaving a substantial portion thereof extending above the surface of the ground. The device is then superimposed on the stake, the upper end of which will extend through the hole 56 in the base 4 and into 15 the hollow upright column 2, thus holding the device securely in position for use, as shown in Fig. 3a.

The cap 58 on the upper end of the hollow upright column 2 may be removed if it is desirable to use the column 2 as a holder 20 for a flag, or as a support for an electric light, in which latter case the necessary wires may extend down through the column to the source of supply of current.

25 It is to be understood that it will not be necessary to fold the extra teeter up when only one teeter is to be used. This may be done, however, when desirable, such as when it is desirable to cover the device in bad 30 weather, or when it is desirable to facilitate moving from space to space, or for shipping or storing.

I claim:

35 1. A device of the character described including an upright column, a revolvable sleeve mounted thereon, laterally extended arms pivotally supported by said sleeve, extensions hingedly supported by said arms, and adjustable arms supported by said exten- 40 sions.

45 2. A device of the character described including an upright column, a revolvable sleeve mounted thereon, a plurality of laterally extended supporting arms pivotally mounted on said sleeve, extension arms hingedly affixed to said supporting arms, and adjustable arms supported by said ex- 50 tension arms.

55 3. A device of the character described, including an upright column, a revolvable sleeve mounted thereon, a plurality of laterally extending supporting arms pivotally affixed to said sleeve, and extension arms hingedly secured to said supporting arms.

60 4. A device of the character described including an upright column, a revolvable sleeve mounted thereon, a plurality of laterally extending supporting arms pivotally affixed to said sleeve, extension arms hingedly 65 secured to said supporting arms, and means for holding said extension arms in the desired position.

65 5. A device of the character described including an upright column, a revolvable sleeve mounted thereon, a plurality of later-

ally extending supporting arms pivotally affixed to said sleeve, extension arms hingedly secured to said supporting arms, and means for holding said extension arms in an approximately horizontal position or an 70 approximately vertical position.

6. The combination of a see-saw and merry-go-round comprising an upright column, a revolvable sleeve adjustably mounted thereon, a plurality of supporting arms pivotally 75 fastened to said sleeve, extension arms hingedly secured to said supporting arms, and laterally adjustable arms supported by said extension arms.

7. The combination of a see-saw and merry-go-round comprising an upright column, a revolvable sleeve mounted thereon, a plurality of teeter boards secured to said sleeve and substantially semi-circular resilient strips secured transversely to the undersides 85 of the outer ends of said teeter boards.

8. A device of the character described including an upright column, teeter-boards hingedly supported thereon, and means for securing said boards in either a substantially 90 vertical or horizontal position.

9. A device of the character described including an upright column, a revolvable sleeve mounted thereon, supporting arms pivotally mounted on said sleeve, teeter arms 95 hingedly affixed to said supporting arms, and means for securing said teeter arms in either a substantially vertical or a substantially horizontal position.

In testimony whereof I affix my signature 100
FRANCIS M. JACOB.
